UNITED STATES PATENT OFFICE.

FRANK J. LOCHEN, OF CHICAGO, ILLINOIS, ASSIGNOR TO IDEAL OIL SAVER COMPANY,
A CORPORATION OF ILLINOIS.

BAFFLE PLATE FOR BOILER FLUES.

Application filed April 16, 1926. Serial No. 102,377.

This invention relates to improvements in baffle plates adapted to be removably inserted in the flues of boilers for interrupting the flow of hot gases therethrough, and for distributing the gases in the flue so that all of the available heat units will be distributed throughout the heating surfaces of the flues thereby increasing the heating efficiency of the boiler, with a material reduction in fuel consumption.

A further object is to provide improved baffles of this character, a plurality of which may be coupled together in fixed spaced relation with respect to each other, and the whole adapted to be readily inserted into and as readily removed from a flue, as a unit.

To the attainment of these ends and the accomplishment of other new and useful objects as will appear, the invention consists in the features of novelty in substantially the construction, combination and arrangement of the several parts, hereinafter more fully described and claimed and shown in the accompanying drawing illustrating this invention; and in which,

Figure 1 is a diagrammatic view in side elevation of a boiler showing a flue in section, and with one series of baffles arranged in the flue.

Figure 2 is a perspective view of one of the baffles from one face thereof.

Figure 3 is a perspective view of another of the baffles from the other face thereof.

Figure 4 is an enlarged longitudinal sectional view of a flue with the baffles in position therein, and with portions broken away.

Figure 5 is an end view of one of the flues showing the baffles therein.

In carrying out this invention there are provided a plurality of baffle members 10 and 11 which are of a diameter somewhat less than the interior diameter of the flue in which they are to be inserted.

Each of the baffles 10 embody a plurality of radially arranged blades 12, which are joined at their base to form a body or hub portion, and which body or hub portion is provided with an opening 13 therethrough.

Each of the baffles 11 also embody a plurality of radially arranged blades which are joined at their base to form a body portion, and which body portion or hub is provided with an opening 15 therethrough.

The blades of the respective baffles are backwardly inclined to give the baffles a gen-

eral conical formation, and the proximate edges of adjacent blades of each of the baffles diverge from the body or apex portion of the baffle outwardly to form passages 16 therebetween, so that the flow of the heated gases through the flue will not be entirely retarded, and at the same time some of the heated gases will be directed against the walls of the flue or pipe as the conical shape of the baffles form with the flue gradually reduced passages for the heated gases between the outer surface of the baffles and the flue, all of the baffles inclining in the same direction throughout the length of the flue.

One of the blades 17 of the baffles 10 is extended so that the periphery thereof will have contact with the wall of the flue and thereby support the baffles.

The baffles which have the extended blade are spaced from each other lengthwise of the flue 18, and a plurality of baffles 11 are arranged between the baffles 10, the blades of each of the baffles inclining rearwardly.

The baffles 10 are so arranged that the extended blades 17 of the respective baffles will be disposed with respect to each other to engage the flue at different points about the flue throughout the length of the flue, for maintaining the baffles in a central position within the flue.

The openings 16 between the adjacent blades of the respective baffles may be arranged in any desired position with respect to each other, that is, in either direct alinement or out of registering relation with respect to each other, so that the heated gases flowing through such openings and from one baffle to another, will be given a rotary or whirling movement as they flow through the flue, the baffles being held stationary, the result being that there will be an intimate mixture of the gases.

The baffles are spaced from each other in directions lengthwise of the flue, in any suitable manner, such as by means of spacing members 19, the ends of which contact with the respective adjacent baffles.

A tie rod 20 passes through the openings 13 and 15 in the respective baffles and also through the spacing members 19. Nuts 21 are threaded upon the extremities of the rod 20 and by adjusting the nuts towards each other upon the rod 20, the baffles together with the spacing members therebetween, will be clamped together so that the device will

constitute a unitary structure adapted to be inserted into and withdrawn from the flue.

The baffles 10 may be arranged at any desired points throughout the length of the structure, and the extended blades 17 contacting with the wall of the flue will not only support the baffles and all of the parts, but will maintain the baffles substantially centrally of the flue.

10 While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. In combination, a plurality of baffles, each of said baffles being of a substantially cone shape, a spacing member disposed between adjacent baffles, and a rod passing through the baffles and spacing member for securing them together as a unitary structure, the baffles being provided with a plurality of extended and substantially V-shaped notches, said notches opening through the body of the baffles, said baffles forming with the flue gradually reduced passages for the gases and constituting the sole means of support for the baffles within the flue.

2. In combination, a plurality of baffles, each of said baffles being of a substantially cone shape, a spacing member disposed between adjacent baffles, a rod passing through the baffles and spacing member for securing them together as a unitary structure, the baffles being provided with a plurality of extended and substantially V-shaped notches, said notches opening through the body of the baffles, and a projection on certain of the baffles for positioning them and constituting the sole supporting means for the baffles within the flue, said baffles forming with the flue gradually reduced passages for the gases, all of the baffles inclining in the same direction throughout the length of the flue.

3. In combination, a flue, a plurality of baffles arranged at intervals in said flue, a rod extending through the centers of the baffles

for connecting them, and means spacing adjacent baffles, said baffles being of a substantially conical formation and forming with the flue gradually reduced passages for the gases between the outer surface of the baffles and the flue, a portion of certain of the baffles being extended beyond the remaining portion of the baffle to engage the flue wall and constituting the sole means for supporting and maintaining the baffles within and substantially centrally of the flue, the said extended portions of the baffles being within the plane of the remaining portion of the body of the respective baffles.

4. In combination, a plurality of baffles each of which is of a substantially cone shape, a rod extending through the centers of the baffles for connecting them, means for maintaining the baffles spaced from each other, all of said parts constituting a unitary structure for free insertion into and removal from a flue as a unit, and means for supporting the structure and for maintaining the baffles substantially centrally of the flue, said baffles being provided with extended substantially V-shaped notches opening through the body of the baffle and also through the rear end thereof, said baffles forming with the wall of the flue gradually reduced passages for the gases.

5. In combination, a plurality of baffles each of which is of a substantially cone shape, a rod extending through the centers of the baffles for connecting them, means for maintaining the baffles spaced from each other, all of said parts constituting a unitary structure for free insertion into and removal from a flue as a unit, and means for supporting the structure and for maintaining the baffles substantially centrally of the flue, all of said parts being disposed entirely within and independent of the flue, said baffles being provided with extended substantially V-shaped notches opening through the body of the baffle and also through the rear end thereof, said baffles forming with the wall of the flue gradually reduced passages for the gases.

In testimony whereof I have signed my name to this specification, on this 13th day of April, A. D. 1926.

FRANK J. LOCHEN.
